UNITED STATES PATENT OFFICE.

FRANK L. SESSIONS, OF COLUMBUS, OHIO, ASSIGNOR TO THE JEFFREY MANUFACTURING COMPANY, A CORPORATION OF OHIO.

LOCOMOTIVE WITH HAULAGE MECHANISM.

1,139,810.

Specification of Letters Patent. Patented May 18, 1915.

Application filed February 13, 1909. Serial No. 477,817

To all whom it may concern:

Be it known that I, FRANK L. SESSIONS, citizen of the United States, residing at Columbus, in the county of Franklin and State of Ohio, have invented certain new and useful Improvements in Locomotives with Haulage Mechanism, of which the following is a specification, reference being had thereto in the accompanying drawing.

10 A locomotive embodying the invention is adapted primarily for use in and about coal or other similar mines for hauling the separate mine cars from the rooms, or other places in which they are loaded, and collecting them into trips or trains to be thereafter hauled from the mine. Under many conditions it is impossible for the locomotive itself, even when provided with an electric cable reel mechanism or other means for 15 supplying electric current, to enter into the rooms to be attached directly to the cars. Under such circumstances use is made of a locomotive having a haulage cable which can be unwound from a reel on the locomotive and its end taken into a room and connected with the car. And then, by suitable power mechanism, the reel is turned and the cable is wound upon it, the car being hauled out to a point closely adjacent the locomotive.

20 One object of this invention is to provide in a locomotive of this general class an improved driving mechanism for the locomotive and for the reel.

25 Another object is to provide an improved mounting for the reel and an improved general arrangement of the reel with respect to the other locomotive parts.

30 For the sake of economy in first cost, and 40 in order to reduce the weight, it is, under many circumstances, found desirable to use a single motor, or a single set of motors, and to provide gearing whereby the motor or motors can be used either to drive the locomotive itself or to drive the reel, or to drive both simultaneously. By my invention I have introduced a differential gearing between the motor on the one hand and the locomotive track wheels and the reel on the

45 other hand, and have provided suitable brake mechanism whereby either the locomotive wheels may be locked and the power transmitted to the reel, or whereby the reel may be locked and the power transmitted to the wheels. Or, if desired, the wheels and

the reel may both be left free and power transmitted to rotate both of them simultaneously. By my invention I have also provided a novel and advantageous mounting for the reel. I mount the reel concentrically 60 with one of the main axles, preferably supporting it directly upon the axle. In this way a very compact arrangement of the operative parts is provided, the driving gearing is greatly simplified, and the reel is 65 firmly held in its true position.

70 In the drawings—Figure 1 is a plan view of the locomotive as a whole. Fig. 2 is a side elevation of the same with parts of the locomotive broken away to show the interior construction. Fig. 3 is a vertical cross section of the rear axle and associated parts. Fig. 4 is a fragmentary elevational view showing the differential gearing.

75 The frame of the locomotive, comprising the side castings 1; 1, and the end castings 2, 3, is supported upon the front and rear axles 4 and 5 respectively, upon which are secured the track wheels 6. At the rear end of the locomotive are arranged the motor-man's seat 7 and the controlling mechanism, such as the controller 8, brake wheel 30, etc.

80 The motors 10, 10, are supported in any suitable manner and are geared by means of the pinions 11, 11 to the gear wheels 12; 12, respectively. Each of these gear wheels 12, 12 is loosely mounted upon one of the locomotive axles 4 and 5 and has journaled within it upon radial axes the bevel pinions 13, 13. The pinions of each gear wheel 12 mesh 85 on one side of the wheel with a bevel gear wheel 14, which is keyed to its axle and is adapted to drive the track wheels and to propel the locomotive bodily. The bevel pinions 13, 13 of each gear wheel 12 also mesh on the other side of the wheel with the bevel gear wheel 15, which is mounted to turn freely with respect to the axle upon which it is sleeved.

90 The gearing which has just been described constitutes a differential power transmitting mechanism for connecting the motor with the wheels and with the drum in such a way that each receives equal torque irrespective of the speed at which it may be permitted to move.

95 The gear wheel 15 is adapted to drive the drum 16 and for that purpose is brought into frictional engagement with the drum in the following manner. The drum is loosely 100

mounted upon the axle so that it can freely turn with respect thereto and can be moved longitudinally. The friction ring 17 on the gear wheel 15 is adapted to coact with the 5 conical face 18 upon the drum. To bring the friction ring into contact with the drum the clutch shifter, indicated as a whole by 19, is employed. The stationary ring 20 of this clutch shifter is formed with a spiral 10 end face 21, which fits against a correspondingly shaped movable ring 22. This ring 22 can be rotated by means of the rod 23 to force the drum against the friction ring 17. By means of the spring 23^a this rod is held 15 yieldingly in such a position as to maintain the drum in frictional contact with the gear wheel 15.

The rod 23 extends through an aperture in the vertical bracket 23^b and is provided 20 near its end with downward opening notches 23^c adapted to engage the bracket. At the end of the rod 23 is a handle 24 and by means of this any one of the several notches 25 can be engaged with the bracket so as to vary the pressure between the drum 16 and the friction ring 17 or to hold the drum entirely out of engagement with the friction ring.

Each gear wheel 15 is provided with an 30 annular recess 25 about which is fitted a brake band 26. The two brake bands 26 are operated in unison by means of the threaded rod 27 and a hand wheel 28 the latter being within reach of the operator as 35 he sits at the rear end of the locomotive. The brake mechanism, indicated as a whole by the numeral 29, is provided as usual for checking or stopping the rotation of the track wheels; and is under the control of 40 the operator by means of the hand wheel 30. Upon the gear wheels 15 are cut the teeth of the sprocket wheels 31, 31, about which is placed the sprocket chain 32. Thus the 45 two motors coöperate to rotate the drum in the same manner that they rotate the track wheels when the proper power transmitting connections are made.

Upon the drum 16 is wound the haulage or drive cable 33 which is conducted from 50 the drum between the guide sheaves 34 mounted in the draw-bar pocket or slot 35 formed in the front end frame 2 of the locomotive. The cable is provided at its free end with a coupling hook 36 by which it 55 can be secured to the car or train of cars which are to be hauled.

The manner in which this locomotive is 60 operated will be quite readily apparent from the description of the working parts. When the locomotive is coupled to a train of cars by means of its draw-bar, and the cable 33 is not in operation, the gear wheels 15 are held stationary by means of the brake bands 26 and the hand wheel 28 and the 65 rotary motion of the motors is transmitted

wholly to the track wheels. When it is desired to hoist loaded cars up steep inclined track-ways from what are known as "dip" rooms, and into which it is not practical to run the locomotives, the locomotive is held 70 stationary at the top of the grade by setting the brake mechanism 29, the motor is started and the drum 16 is rotated to wind up the cable and haul the cars out of the various rooms in which they have been loaded. During such operation the brake bands 75 26 are released and the spring operated clutch shifter 19 is released so that the drum is held in frictional contact with the gear 15.

When it is so desired the cable can be used 80 as a coupler in hauling the cars along the entry-way from room to room while they are being gathered. It is also possible with this locomotive, if it should be found advantageous, to lower the cars into the rooms by holding the gear wheels 15 stationary and controlling the unwinding of the cable 33 by means of the clutch shifter 19, which can be used to increase or decrease the friction 85 between the drum and the stationary gear 90 wheel 15.

When the locomotive is pulling a car or train of cars and an exceptionally steep grade is about to be traveled, the cable drum can be released so that the car or cars will 95 remain at the bottom of the grade while the locomotive ascends it and after the locomotive has reached the top the brakes can be set and the hoisting mechanism employed 100 to pull the cars up the grade after the locomotive.

What I claim is:

1. In a gathering locomotive, the combination with a frame, axles and track wheels, of a motor connected to the track wheels, a 105 rotatable drum, a cable connected at one end to the drum to be wound thereon and adapted to be attached at the other end to a car, power transmitting mechanism comprising a friction clutch between the motor and drum; means for controlling the clutch, and means for resisting the movement of the clutch element operatively nearest the motor, the clutch being thus adapted for resisting 110 the rotation of the drum in the unwinding direction.

2. In a gathering locomotive, the combination of a frame, a pair of axles, drive wheels on the axles, a motor geared to one axle and rotatable independently thereof, a 120 motor geared to the other axle and rotatable independently thereof, a rotatable drum, a cable connected at one end to the drum to be wound thereon and adapted to be attached at the other end to a car, power 125 transmitting mechanism between one motor and the drum, and power transmitting mechanism between the other motor and the drum.

3. In a gathering locomotive, the combi- 13

ination with a frame, axles and drive wheels, of a rotatable drum, brake mechanism for the drive wheels, brake mechanism for the drum, a motor, and power transmitting mechanism connecting the motor with the drive wheels and with the drum, the said mechanism being arranged to automatically drive the wheels when the drum brake mechanism is applied and to automatically drive the drum when the wheel brake mechanism is applied.

4. In a gathering locomotive, the combination with a frame, an axle and two track wheels rigidly connected to the axle, of a motor, a rotatable drum, a cable connected at one end to the drum to be wound thereon and adapted to be attached at the other end to a car, a differential power transmitting mechanism, a power connection between the motor and the driving element of the said differential mechanism, a power connection between one driven element of the differential mechanism and the drum, a permanently engaged power connection between the other driven element of the differential mechanism and the axle and track wheels, means for braking the wheels, and means for braking the drum.

5. In a gathering locomotive, the combination with a frame, axles and track wheels, of a rotatable drum, a haulage cable connected at one end to the drum to be wound thereon and adapted to be connected at the other end to a car, manually controllable means for resisting the rotation of the track wheels, a motor, a differential power transmitting mechanism having its driving element connected to the motor, a connection between one driven element of the differential mechanism and the track wheels, a connection comprising a manually controllable friction clutch between the other element of the differential mechanism and the drum, and manually controllable means for resisting the rotation of the element of the friction clutch which is operatively nearer the differential mechanism.

6. In a gathering locomotive, the combination with a frame, axles and track wheels, of a rotatable drum, a haulage cable connected at one end to the drum to be wound thereon and adapted to be attached at the other end to a car, a brake for the track wheels, a brake for the drum, two separate motors, two separate differential power transmitting mechanisms each having its driving element connected to one of the motors, two power connections each between one driven element of one of the differential mechanisms and one of the axles, and a power connection between the other driven elements of the differential mechanisms and the drum.

7. In a gathering locomotive, the combination with a frame, axles and track wheels,

of a rotatable drum, a haulage cable connected at one end to the drum to be wound thereon and adapted to be attached at the other end to a car, a brake for the track wheels, a brake for the drum, two separate motors, two separate differential power transmitting mechanisms each having its driving element connected to one of the motors, two power connections each between one driven element of one of the differential mechanisms and one of the axles, and a power connection comprising a manually controllable clutch between the other driven elements of the differential mechanisms and the drum.

8. In a gathering locomotive, the combination with a frame, axles and track wheels, of a drum rotatably mounted directly upon one of the axles but movable rotatably and longitudinally independently thereof, a cable connected at one end to the drum to be wound thereon and adapted to be connected at the other end to a car, a brake for the track wheels, a brake for the drum, a motor operable independently of the track wheels, power transmitting mechanism between the motor and the drum, the said mechanism comprising one element fixed against longitudinal movement with respect to the axle and another element rigidly connected with the drum, and manually controllable means for moving the drum longitudinally of the axle to bring the two said elements of the power transmitting mechanism into or out of engagement with each other.

9. In a gathering locomotive, the combination with a frame, axles and track wheels, of a drum rotatably mounted directly upon one of the axles but rotatable independently thereof, a cable connected at one end to the drum to be wound thereon and adapted to be connected at the other end to a car, a brake for the track wheels, a brake for the drum, a motor operable independently of the track wheels, a differential power transmitting mechanism mounted on the axle with its driving element rotatable concentrically therewith, means for connecting the motor with the driving element of the differential mechanism, and means for connecting the driven elements of the differential mechanism respectively with the track wheels and the drum.

10. In a gathering locomotive, the combination with a frame, axles and track wheels, of a drum rotatably mounted directly upon one of the axles but rotatable independently thereof, a cable connected at one end to the drum to be wound thereon and adapted to be connected at the other end to a car, a brake for the track wheels, a brake for the drum, a motor operable independently of the track wheels, a differential power transmitting mechanism mounted on the axle with its driving element rotatable concentric-

cally therewith, means for connecting the motor with the driving element of the differential mechanism, means for connecting one driven element of the differential mechanism with the track wheels, and means comprising a manually controllable clutch for connecting the other driven element of the differential mechanism with the drum.

11. In a gathering locomotive, the combination with a frame, axles and track wheels, of a drum rotatably mounted directly upon one of the axles but rotatable independently thereof, a cable connected at one end to the drum to be wound thereon and adapted to be connected at the other end to a car, a brake for the track wheels, a brake for the drum, two separate motors, two separate differential power transmitting mechanisms each having its driving element connected to one of the motors, two power connections each between one driven element of one of the differential mechanisms and one of the axles, and a power connection between the other driven elements of the differential mechanisms and the drum.

12. In a gathering locomotive, the combination with a frame, axles and track wheels, of a drum rotatably mounted directly upon one of the axles but rotatable independently thereof, a cable connected at one end to the drum to be wound thereon and adapted to be connected at the other end to a car, a brake for the track wheels, a brake for the drum, two separate motors, two separate differential power transmitting mechanisms

each having its driving element connected to one of the motors, two power connections each between one driven element of one of the differential mechanisms and one of the axles, and a power connection between the other driven elements of the differential mechanisms and the drum.

13. In a gathering locomotive, the combination with a frame, axles and track wheels, of a rotatable drum, a haulage cable connected at one end to the drum to be wound thereon and adapted to be connected at the other end to a car, manually controllable means for resisting the rotation of the track wheels, manually controllable means for resisting the rotation of the drum, a motor, a differential power transmitting mechanism mounted on the axle with its driving element rotatable concentrically therewith, means for connecting the motor with the driving element of the differential mechanism, and means for connecting the driven elements of the differential mechanism respectively with the track wheels and the drum.

In testimony whereof I affix my signature, in presence of two witnesses.

FRANK L. SESSIONS.
